UNITED STATES PATENT OFFICE.

WILLIAM VON BAUMBACH, OF MILWAUKEE, WISCONSIN.

ICE-BOX OR REFRIGERATOR LINING.

1,017,633.

Specification of Letters Patent.

Patented Feb. 13, 1912.

Application filed March 9, 1906. Serial No. 305,045.

To all whom it may concern:

Be it known that I, WILLIAM VON BAUMBACH, a citizen of the United States, residing at Milwaukee, in the county of Milwaukee and State of Wisconsin, have invented certain new and useful Improvements in Ice-Box or Refrigerator Linings, of which the following is a specification, reference being had to the accompanying drawing, forming 10 a part thereof.

The main objects of this invention are to produce independently of the casing or housing, a strong durable ice box or refrigerator lining which will not leak, which can be 15 easily kept clean, and which will avoid waste of ice, and generally to simplify and improve the construction of devices of this class.

It consists in certain novel features of construction as hereinafter particularly described and pointed out in the claim.

In the accompanying drawing like letters designate the same parts in both figures.

Figure 1 is a front elevation of an ice box 25 or refrigerator lining constructed in accordance with the invention; and Fig. 2 is a vertical section of the same on the line 2 2, Fig. 1.

The lining *a*, which may be made of various forms and dimensions, is shown for the purpose of illustration as of rectangular form and having five closed sides. It is made in one piece of some suitable plastic material. A composition consisting of the 35 following ingredients in about the following proportions is well adapted for the purpose: 100 pounds asbestos fiber, 50 pounds wood fiber (sawdust), 100 pounds liquid magnesite. This composition, which makes a good 40 nonconductor of heat, is capable of being easily molded into the desired form and produces a tough durable and comparatively light monolithic structure impervious to air and moisture. It is of a close homogeneous 45 texture and molds with even smooth surfaces which may be enameled or otherwise finished if desired. It will not break or crack easily, being sufficiently elastic and tough to resist the blows and strains to which ice box or 50 refrigerator linings are ordinarily subjected.

The internal corners of the lining are

preferably coved or rounded as shown at *b*, to prevent fracture along the lines of the angles and to avoid sharp corners or creases in which dirt will collect and which it is 55 difficult to keep clean.

The lining is provided with an ice receptacle and shelf-supporting frame which may be conveniently constructed as shown, of galvanized iron pipe or metal rods. The 60 upright members *c* of this frame are threaded at the ends and secured in the upper and lower ends of the lining by nuts and washers *d*, both inside and outside of the lining. The ends of the lining where the 65 uprights *c* are secured therein, are preferably reinforced on the outside by metal strips *e*, through perforations in which said members pass, the washers of the outer nuts being seated against said strips. The uprights 70 *c* are connected by cross members *f*, which may be attached thereto as shown, by ordinary T fittings or couplings *g*. These cross members support an ice receptacle (not 75 shown) or a shelf *h*, on which such receptacle is carried, while extra shelves such as *h*, for holding articles to be kept in the ice box or refrigerator, may be removably and adjustably mounted on said uprights.

The ice box or refrigerator will of course 80 be provided on the open side with a suitable door which may be made of or lined with the same composition or material of which the main lining itself is constructed.

The lining may be permanently built into 85 a house or other structure, or for a portable refrigerator, may be inclosed in a casing of wood, tile, metal or other suitable material, either with or without an interlining or filling of asbestos, sawdust or other material 90 usually employed for the purpose in the construction of refrigerators.

Various changes in the form and details of construction of the lining and the nature and proportions of the ingredients of the 95 composition entering into the construction of the lining may be made without departing from the principle and intended scope of the invention.

I claim:

An ice box or refrigerator lining having 100 its top and bottom, back, and two side walls

formed integral with each other to constitute a seamless lining without joints, having the internal corners along the lines of the angles at the sides and back of the lining curved, and consisting of a non-conducting, non-contractible and non-expansible composition formed of substantially equal parts of asbestos and magnesite and materially smaller

percentage of wood fiber, substantially as described.

In witness whereof I hereto affix my signature in presence of two witnesses.

WILLIAM VON BAUMBACH.
